UNITED STATES PATENT OFFICE.

OLIVER WESTON, OF CLEVELAND, OHIO.

WRENCH.

1,080,132.

Specification of Letters Patent.

Patented Dec. 2, 1913.

Application filed May 16, 1912. Serial No. 897,629.

To all whom it may concern:

Be it known that I, OLIVER WESTON, a citizen of the United States, residing at Cleveland, in the county of Cuyahoga and State 5 of Ohio, have invented certain new and useful Improvements in Wrenches, of which the following is a specification.

This invention relates to improvements in wrenches and is designed particularly 10 for pipe wrenches.

The main object of the invention is to provide a wrench for operating different sizes of pipe or nuts, the same being accomplished by the use of a removable jaw having a plurality of differently inclined toothed surfaces and so arranged with relation to a stationary jaw that it forms different angles therewith.

Another object of the invention is to provide 20 a removable toothed jaw which may be replaced by a new jaw when the same has become ineffective from wear.

With the above and other objects in view, the invention consists in certain combinations and arrangements of the parts herein-after fully described in connection with the accompanying drawings illustrating a preferred embodiment thereof, and the novel features will be distinctly pointed out in the 30 appended claim.

In the drawings like characters of reference indicate corresponding parts.

Figure 1 is a side elevation of a wrench constructed in accordance with my invention, Fig. 2 is a view of Fig. 1 looking at the under edge, Fig. 3 is a perspective view of the stationary jaw end of the wrench, the removable jaw being omitted, Fig. 4 illustrates the relation between the stationary 40 jaw and the removable jaw when the latter is reversed from the position shown in Fig. 1, and Fig. 5 shows a removable jaw having teeth on several differently inclined surfaces.

Referring to the drawings, 1 represents 45 the handle, which is preferably of the shape shown but may be of any suitable form, and 2 the stationary jaw, both of which parts are connected by a diagonal enlarged portion 3 having an inclined forward face 4 and a 50 similar rear face 5. The enlarged portion 3 is provided with a square tapering opening

6 which extends therethrough from its rear face 5 to the forward face 4. Said opening 6 is for the purpose of receiving the correspondingly shaped shank end 7 of a removable 55 jaw 8, and is so arranged on an inclination with relation to the stationary jaw 2, that the removable jaw when in normal position forms an angle therewith.

In order to provide for adjustment of the jaws to take different sizes of pipe or nuts, the removable jaw 8 is made with differently inclined toothed surfaces as shown at 9 and 10, and when said jaw is arranged as shown in Fig. 1, the toothed surface 9 forms a 65 more acute angle with the stationary jaw 2 than when its other toothed surface 10 is arranged in the same relation to the stationary jaw as illustrated in Fig. 4. As the shank end 7 of the removable jaw tapers from the 70 rear and is wedge shaped, the teeth of the jaw when biting into the material being operated upon tends to draw the shank end of the removable jaw more securely into the tapering opening 6. As illustrated by Fig. 75 5 the removable jaw may be made with its sides or edges also having differently inclined toothed surfaces 11 and 12 from its toothed surface 13, which will allow of a more varied angular adjustment with relation to the stationary jaw.

In a wrench constructed as described, the removable jaw may be changed in the tapering opening 6 so that its toothed surfaces will make different angles with the stationary 85 jaw and thereby fit different sizes of pipe or nuts; and when the teeth become worn, the removable jaw may be replaced by a new toothed jaw.

Having fully described my invention what 90 I claim is:

A wrench comprising a handle, a stationary jaw, an enlarged diagonally arranged portion connecting the base of the stationary jaw to the upper end of the handle, the 95 enlarged portion being provided with a square opening arranged on an acute angle with relation to the stationary jaw, the opening being smaller at its forward end than at its rear end with converging walls 100 forming a tapering opening, a jaw having differently inclined toothed surfaces and

terminating in a square tapering opening to hold the last mentioned jaw so that its inclined toothed surfaces will form different acute angles with the stationary jaw and for wedging itself into said tapering opening on account of the pulling pressure exerted by the teeth of said jaw engaging the material being operated upon during the

manipulation of said handle, substantially as described.

10

In testimony whereof I affix my signature in presence of two witnesses.

OLIVER WESTON.
